UNITED STATES PATENT OFFICE.

ELMER L. LANG AND GEORGE H. LANG, OF BOSTON, MASSACHUSETTS.

MARKING MACHINE.

Application filed October 9, 1922. Serial No. 593,416.

This invention relates to marking machines of the type comprising a platen or work support and a printing head movable toward and from the platen to make the printed impression. Each printing head is provided with a plurality of independently adjustable type wheels.

One feature of our invention relates to a novel manner of locking the adjustable type wheels in place and for setting the type wheels individually.

In the drawings, Fig. 1 is a side view of a marking machine embodying our invention.

Fig. 2 is a partial front view thereof.

Fig. 3 is a transverse section through the printing head.

Fig. 4 is a section through the printing head on the line 4—4, Fig. 3.

The marking machine herein shown is of that general type comprising a stand or frame 1, having a head 2, in which reciprocates vertically a plunger 3, carrying a printing head 4, said printing head movable toward and from a platen or work support 5, on which the work is supported.

The printing head herein shown is constructed with a plurality of individually adjustable type wheels 6, said type wheels being rotatively mounted on a hollow sleeve 7, carried in the printing head. Each type wheel is provided with a plurality of type characters, as is usual in machines of this class. The printing head may be given its vertical movement by any suitable mechanism.

The type wheels are formed with notches 8, between the type characters, as is usual in machines of this character, and said wheels are locked from turning movement by a locking bar 9, which fits the aligned notches of the type wheels. This locking bar is formed with a notch 10 of the width of the type wheels 6, and said locking bar is slidably mounted in guides 11, so that the notch 10 can be brought into register with any one of the type wheels 6. The particular type wheel which is in register with the notch is free to be turned while the others are locked from turning movement as will be obvious.

For adjusting the type wheel which is thus unlocked, we have provided a setting dog 12, which is carried by a slide 13, and operates in a groove 14, formed in the supporting sleeve 7. This slide 13 is connected to a collar 15 which is fast on a member 16 that telescopes into the supporting sleeve 7.

The locking bar 9 is also connected to this collar, so that the locking bar and setting member always move in unison. The connection between the locking bar 9 and the collar 15, however, is one which permits the collar and its supporting member 16 to turn about their axes. This connection comprises a ring 17, which is swivelled on the collar 15, and to which the end of the locking bar 9 is secured by means of a clamping screw 18.

In setting any type wheel, the collar and member 16 are moved longitudinally of the sleeve 7 to bring the notch 10 opposite the type wheel which is to be set, thus unlocking said type wheel.

Each type wheel is provided on its interior with a plurality of notches 19, one for each type character, and when the type wheels are locked in operative position, the notches of the various type wheels are in alignment with each other. These notches are constructed to receive the dog 12 and the construction is such that when the collar 15 is adjusted to bring the notch 10 of the locking bar into register with any type wheel 6, the setting dog 12 will be occupying one of the notches of said type wheel. This setting dog 12 it will be remembered occupies a groove 14 in the sleeve 7, which is rotatably mounted in the head. Therefore the rotation of the sleeve 7 through the knurled head 21, will operate through the setting dog 12 to turn the particular type wheel which is unlocked by the locking bar.

It is sometimes desirable to employ a wide type wheel capable of supporting type characters, each of which represents a complete word. This is especially desirable in the manufacturing of shoes, where it is desired to stamp shoes or parts thereof, or the cartons therefore, with the size number, case number, and some word describing the character of the shoes.

We have herein shown the printing head as including one type wheel 22, which is much wider than the other type wheels and which is thus adapted to have on its periphery type characters each of which are constructed to form printed words.

In order to provide for unlocking this wide type wheel to permit it to be set, we have provided the locking bar 9 with a movable section 23, which has a width equal to that of the wide type wheel, and which when removed, produces a notch or opening in the bar as wide as said wide type wheel, so

that when the locking bar is adjusted to bring this wide notch opposite the wide type wheel then the latter will be unlocked.

This movable section 23, is shown as pivoted to the locking bar 9 at 24 and when it is swung into line with the bar, it forms part of the locking portion thereof, but when it is swung into its open position, shown in Fig. 4, it provides the wide notch that permits the 10 unlocking of the wide type wheel 22.

The type characters are inked by means of an inking roll 25, herein shown as carried by two swinging arms 26, which are pivotally connected at their upper ends, as shown 15 at 27, to uprights 28, extending from the printing head. The swinging arm 26 carries the ink roll across the surface of the type characters when the printing head is elevated, and when said printing head is 20 depressed into printing position said arms swing into dotted line position Fig. 1, thereby carrying the printing roll against an ink-distributing roll 29. This ink-distributing roll is rotatably mounted in a bracket 30, secured to the frame 1. Said bracket also 25 supports the ink reservoir 31, in which operates an ink supply roll 32.

33 indicates a transfer roll which is journaled in a rocking member 34 pivoted to 30 the bracket at 35, rocking movement of said member carrying the transfer roll from the ink-distributing roll 29 to the supply roll 32. The rocking member 34 is acted on by 35 a spring 36 which is secured at one end to the bracket 30 and at the other end to a pin 71 extending from the rocking member, the spring tending to hold the transfer roll 33 in contact with the ink-distributing roll 29.

37 indicates a dog pivoted to the rocking 40 member 34 and having a notch 39.

The swinging arm 26 carries a projection 38 at its lower end which co-operates with the dog 37 to swing the rocking member. When the dog is in the full line position 45 Fig. 1 then the notch 39 is in the position to receive the projection 38 as the arms 23 swing backwardly and when this condition obtains the rocking member remains stationary but if the dog is turned to carry the 50 notch 39 out of the path of movement of the projection 38 then when the arm 26 swings backwardly said projection will engage the dog and turn the rocking member to swing the transfer roll into contact with 55 the ink-distributing roll. The transfer roll will then take up ink and when the arms 26 swing forward again this transfer roll will be carried into contact with the ink-distributing roll 29 and will thus supply 60 fresh ink thereto. This inking device, however, is not herein claimed.

The platen 5 is yieldingly sustained so that it will move downwardly when pressure is applied thereto.

65 This platen is shown as provided with a

plunger 48, operating in a guide 49, formed in a bracket 50, by which the platen is supported, the lower end of the plunger is pivotally connected to a lever 51, which is pivoted at 52, to said bracket 50, and the 70 said lever is acted upon by a spring 53, which tends to raise the platen. Any downward movement of the platen, therefore, is against the action of the spring 53.

The plunger 48 is provided with ratchet 75 teeth 54 with which a locking pawl 55 co-operates, said locking pawl being slidably mounted in the bracket guide 49 and being acted on by springs 56. This locking pawl 55 when in operative position prevents upward movement of the platen, although the latter is at all times free to move downwardly. The locking pawl is withdrawn at proper times by an arm 58 fast on a rock shaft 57, the latter having an arm 60 rigid therewith to which is connected a link 61 which is urged upwardly by a spring 62 and is depressed at the time that the printed impression is made by means of a cam 63 which is mounted on a shaft 64 operating in 80 timed relation with the movement of the head 4. This cam engages a roll 65 on the link 61 and the latter has a slot 66 through which the shaft 64 extends. This construction of locking and unlocking the platen is 85 not, however, herein claimed.

While we have illustrated herein a selected embodiment of our invention we do not wish to be limited to the constructional features shown.

We claim:

1. In a marking machine, the combination with a hollow supporting sleeve, of a plurality of type wheels rotatively mounted thereon, one of which type wheels is wider than the other, a locking bar engaging the type wheels and locking them from rotation, said bar having a notch of a width corresponding to the width of the narrower type wheels, and a movable section corresponding to the width of the wide type wheel, said locking bar being movable to bring the notch opposite any narrower type wheel or the movable section opposite the wide type wheel, said section when removed releasing said wide type wheel, and means to set the particular type wheel thus released.

2. In a marking machine, the combination with a hollow supporting sleeve having a longitudinal groove, of a plurality of type wheels rotatably mounted thereon, each type wheel having a notch, a type-setting dog slidably mounted in said groove and adapted to be shifted into engagement with a notch in any one of the type wheels, said sleeve being rotatably mounted thereby to adjust the particular type wheel with which the dog has engagement and a locking bar situated exterior to the type wheels and locking them from movement, said bar being

adjustable longitudinally to release individual type wheels.

3. In a marking machine, the combination with a hollow supporting sleeve adapted to 5 rotate about its axis, said sleeve having a longitudinal groove, of a plurality of type wheels rotatably mounted on said sleeve, each type wheel having a plurality of notches, a setting dog slidably mounted in 10 said groove and adapted to be brought into engagement with a notch of any type wheel,

a member movable axially of said sleeve and to which the setting dog is connected, and a locking bar secured to said member and operating to lock all the type wheels except 15 the one with which the setting dog has engagement.

In testimony whereof, we have signed our names to this specification.

ELMER L. LANG.
GEORGE H. LANG.
